UNITED STATES PATENT OFFICE.

MILTON C. TULLY, OF LOUISVILLE, KENTUCKY.

SASH-FASTENER.

SPECIFICATION forming part of Letters Patent No. 425,528, dated April 15, 1890.

Application filed August 28, 1889. Serial No. 322,193. (No model.)

To all whom it may concern:

Be it known that I, MILTON C. TULLY, a citizen of the United States, residing at Louisville, in the county of Jefferson and State of Kentucky, have invented certain new and useful Improvements in a Combined Lock and Lifter for Window-Sash; and I do hereby declare the following to be a full, clear, and exact description of the invention, such as will enable others skilled in the art to which it appertains to make and use the same.

My invention relates to devices for locking and raising the sash of windows, and particularly of the windows of railway-coaches; and my object is to provide a combined sash lock and lifter by means of which the sash is unlocked as soon as the lifter is grasped to raise it and is locked as soon as the lifter is released, and whereby the lower sash of a window when down to the bottom or up to the top of the window-frame is securely locked and when between those points will retain its position without being shaken down by the ordinary motion of a car. I accomplish these objects by the means illustrated in the accompanying drawings, in which—

Figure 1 is a perspective view of my invention as it appears attached to the bottom piece of a window-sash. Fig. 2 is a view of a longitudinal vertical section of the sash-frame, showing the bolt in perspective. Fig. 3 is a sectional view through the line xx of Fig. 1.

Similar letters refer to similar parts throughout the several figures.

35 a represents the bottom piece of the sash. b is a slotted metal frame set in the center of a .

c is the lifter made integral with a plate e , which is screwed to the bottom of the mortise in the sash-piece a .

40 $d d$ are finger-clamps riveted in the sides of the frame b .

ff are expanding levers riveted at $i i$ to a piece of metal g , set in the frame a and having 45 the narrow arms $p p$ beyond g , the ends of which work in a slot p' in a bolt J . The lock-bolt J extends from the levers to a point a little beyond the edge of the sash in a circu-

lar hole pierced longitudinally through the bottom of the sash, so as to catch in the opening m in the window-frame n .

50 k is a spiral spring surrounding the bolt J and let in the circular opening in the sash-piece a to a point q' , where this opening is abruptly reduced to form a seat for the spring k , acting against the shoulder q on the bolt J .

The operation of my invention is as follows: When it is desired to raise a sash provided with my lock and lifter, the finger-clamps $d d$ are grasped between the thumb and first finger, pressing them toward the lifter C . This raises the levers ff , pushes the arms $p p$ down in the slot p' , and pulls the bolt J out of the socket m . The sash can then be lifted with one hand, and as soon as the grasp on the finger-clamps is let go the spring k presses the bolt firmly against the sides of the window-frame n and holds the sash in position, or sockets may be placed at suitable intervals along the sash-frame to receive the ends of the bolt. Without sockets the pressure of the spring will hold the sash up against ordinary jarring. The finger-clamps $d d$ can serve as lifters and the lifter c be dispensed with; but in practice I prefer to use the lifter c for the additional strength it gives.

Having thus described my invention, what I claim as new, and desire to secure by Letters Patent, is—

In a sash lock and lifter, the combination, 80 with a lock-bolt having a shoulder near the locking end, a spiral spring resting against the shoulder, and a slot p' in its inner end, working in a circular opening pierced longitudinally through the bottom piece of a sash-frame from the edge to near the middle, of the expanding levers ff , finger-clamps $d d$, a lifter c , and a mortised frame a , substantially as described, and for the purposes set forth.

85 In testimony whereof I affix my signature in presence of two witnesses.

MILTON C. TULLY.

Witnesses:

B. DU PONT,

A. S. DIETZMAN.
